UNITED STATES PATENT OFFICE.

JASPER LEANDER ACKERMAN, OF MONON, INDIANA.

BREAK-LEVER LOCK FOR GUNS.

SPECIFICATION forming part of Letters Patent No. 667,051, dated January 29, 1901.

Application filed October 16, 1899. Serial No. 733,811. (No model.)

To all whom it may concern:

Be it known that I, JASPER LEANDER ACKERMAN, of Monon, in the county of White and State of Indiana, have invented a new and useful Improvement in Break - Lever Locks for Guns, of which the following is a specification.

In the patent granted to me September 26, 1899, there is shown and described a means for locking the break-lever of a breech-loading gun to prevent it from being opened by unauthorized persons, in which device a bolt entering the lever was actuated by a rotary barrel turned by a detachable key.

My present invention comprises an organization of devices for accomplishing this result, in which an external slide is made to lock said lever either through a bolt or by a direct engagement, or both, and in which the slide may be so organized as to constitute the safety of the hammerless gun, as hereinafter more fully described with reference to the drawings, in which—

Figure 1 is a longitudinal section of the grip portion of the gun, showing the locking of the break-lever through a slide which acts both directly and also through a bolt and in which the slide also forms the "safety" to lock the triggers, the gun being shown in the locked position and the slide also locked by a rotary barrel and key. Fig. 2 is a similar view, the parts being shown in an unlocked position. Figs. 3 and 4 are two views showing closed and open positions, respectively, in which the slide acts upon the locking-bolt through the intervention of a lever. Fig. 5 is a modification in which the slide operates upon the bolt directly through a cam-slot; and Fig. 6 is a plan of a further modification in which the bolt does not enter the lower side of the break-lever, but comes up on one side of it. Fig. 7 is a detail of a further modification.

Referring to Figs. 1, 2, and 6, A represents the break-lever, which has a recess a on its under side to receive the end of the locking-bolt B, which is constructed as a lever fulcrumed upon a pin b. To the lower end of the lever is jointed a bar C, which at its rear end is jointed to a downward extension d from the external slide D, moving over a longitudinal slot in the grip of the gun. From this

downward extension d of the slide another bar E extends to and is jointed to the top of a lever G, fulcrumed on a support g and carrying on its sides a pin g', that engages with the triggers. When the slide D is pushed forward, as in Fig. 1, the lever B is thrown into the recess of the break-lever A and the lever G is turned to bring its pin g' against the triggers. This not only locks the triggers, so that the gun is safe, but also locks the break-lever A, so that unauthorized persons may not open the gun and remove the cartridges or otherwise tamper with the same.

In some cases I may not employ the lock-lever B and bar C, but may make the forward end of the external slide D bifurcated to embrace and hold the rear end of the break-lever, as shown in Figs. 1 and 6, which makes a simpler and more direct lock, or both locking devices may be employed.

As another modification of my invention I may, as seen in Figs. 3 and 4, make the locking-bolt B' to slide vertically and operate it through a lever L and spring l, worked by a cam-face d' on the external slide D, or, as in Fig. 5, the slide D may have a horizontal extension d'', provided with an inclined slot d'', in which a pin attached to the lower end of the bolt plays and is directly operated by the slide.

To lock the slide D in either its forward or retracted position, a small lock of the "Yale" pattern is arranged with its rotary barrel H in vertical position just behind the slide, and has a cam-head H' on its lower end. A lever-catch K is fulcrumed at the forward edge of the lock-case and its forward end is pulled up by a spring F. On the rear end of this catch the cam-head H' of the rotary barrel of the lock bears. When this cam-head is turned into one position, as shown in Fig. 1, it allows the spring F to pull the catch K up behind the extension d of the slide, so that the slide cannot be pulled back; but when the cam-head H' is turned it acts upon the rear end of the catch and draws down the front end of the catch, so that it is out of the way of the rearward movement of the slide extension, the hooked end of the catch rising after the slide is drawn back and hooking in front of the extension d, as shown in Fig. 2, so that the slide is locked also in its open position. The

rotary barrel H, with cam-head H', is operated by a key J, which is carried by the owner of the gun, so that he alone has control of the slide.

5. As a further modification of my invention instead of recessing the under side of the break-lever for the entrance of the bolt I may arrange a hole in the gun-stock or frame-plate on one side of the lever, as shown at a', Fig. 6, in which case the bolt will rise in front of the lever in the path of the swing, and so prevent it from being deflected.

In Fig. 7 I show a further modification in which the slide D' has a tongue that enters a notch in the lever A instead of being made

20 forked and embracing it, as in Fig. 6. I would also have it understood that various other modifications may be made without departing from my invention, the leading feature of which is to be found in the combination, with the break-lever, of an external slide arranged to lock said lever either directly or indirectly.

Having thus described my invention, what I claim as new, and desire to secure by Letters Patent, is—

25 1. The combination with the break-lever in a breech-loading gun; of an external slide arranged to lock said lever and a separate locking mechanism for the slide substantially as and for the purpose described.

2. The combination with the break-lever in a breech-loading gun; of an external slide arranged to lock said lever, and an independent lock for locking the slide arranged behind the same, substantially as and for the purpose set forth.

3. The combination with the break-lever, and the trigger mechanism in a breech-loading gun; of an external slide arranged to lock

both the break-lever and the trigger mechanism and a separate lock for the external slide, as and for the purpose set forth.

4. The combination with the break-lever, and the trigger mechanism in a breech-loading gun; of an external slide arranged to lock both the break-lever and the trigger mechanism, and an independent lock for locking said slide as described. 45

5. The combination with the break-lever in a breech-loading gun; of an external slide arranged to engage with the break-lever externally and directly, and a locking device for holding said slide to such engagement substantially as described. 50

6. The combination in a breech-loading gun; of an external "safety-slide" and a lock and key for locking said slide arranged behind the slide substantially as and for the purpose described. 55

7. The combination with an external safety-slide, having a downward extension; of a rotary barrel-lock said barrel having a key opening outside the gun and a rigid cam-head inside the gun, and a spring-actuated lever-catch having one end acted on by the cam-head of the barrel and the other arranged to engage with the slide extension and lock the same substantially as described. 60

8. The combination with the break-lever, a locking-bolt engaging the same, and an external slide acting upon said bolt and a locking device for the external slide substantially as described. 65

In testimony whereof I have signed my name to this specification. 70

JASPER LEANDER ACKERMAN.
